Primary Examiner — Natasha Vujcic(74) *Attorney, Agent, or Firm* — Alleman Hall Creasman & Tuttle LLP(57) **CLAIM**

The ornamental design for an air-conditioning outlet, as shown and described.

DESCRIPTION

FIG. 1 is a front view of an air-conditioning outlet showing my new design.

FIG. 2 is a left side view of the air-conditioning outlet of FIG. 1.

FIG. 3 is a right side view of the air-conditioning outlet of FIG. 1.

FIG. 4 is a top view of the air-conditioning outlet of FIG. 1.

FIG. 5 is a bottom view of the air-conditioning outlet of FIG. 1; and,

FIG. 6 is a perspective view of the air-conditioning outlet of FIG. 1.

The rear view is a mirror image of the front view and thus is omitted.

1 Claim, 3 Drawing SheetsFIG. 1
